AIR CONDITIONING DEVICE

Arthur W. Conley, Shaker Heights, Ohio, assignor to The Corozone Air Conditioning Corporation, Cleveland, Ohio

Application March 16, 1936, Serial No. 70,551

5 Claims. (Cl. 204—32)

This invention relates to air conditioning devices and has for its principal object to provide a simple, cheap and effective ionizing device in which the parts are compactly and effectively arranged for disposition in a small space and in which a novel and superior arrangement is provided for the component parts.

A further object is to provide a simpler arrangement of insulation than has been previously employed and to combine such novel manner of insulation in a very effective way with the mounting construction for the high tension ionizing mechanism.

Other objects will be in part apparent and in part pointed out in connection with the accompanying drawings wherein Fig. 1 is a vertical longitudinal section taken through the present preferred embodiment of the device; and Figs. 2 to 5 inclusive are sections on the lines 2—2 to 5—5 inclusive of Fig. 1.

In the drawings, the numeral 10 indicates a bottom plate forming a bottom wall of the housing, the numeral 11 indicates the side walls thereof which are perforated as indicated at 12 and the numeral 13 indicates the top wall which may be fixedly secured to the side walls 11. The bottom wall 10 may be secured to the vertical walls 11 by suitable screws 14 and protective feet 15 may be provided for preventing the device from marring furniture on which it may be placed.

Suitably secured to the wall 10, preferably by means of the attaching screws 16 by means of which the feet 15 are secured, are brackets 17 which preferably are of inverted U shape, positioned one at each end and having terminal portions 18 bent over at right angles, in the same direction, for securing to the screws 16. By bending the portions 18 in the same direction, I provide a space within the casing to accommodate the transformer windings, as will be pointed out. Secured to the bight portion of the inverted U-shaped element 17 is a transformer core 19 which may take the form of a rectangular laminated iron block having at each end centrally located openings for reception of the transformer windings 20 and 21. These windings may pass through the said openings and encircle one edge portion of the element 19.

Mounted on top of the block 19 at each end and preferably immediately above the elements 17 are U-shaped brackets 22 having their bight portions secured to the block 19 and terminating at their upper ends in bent over portions 23 extending in the same direction as the corre-

sponding bent over portions 18 of the bracket 17. It will thus be seen that the construction described so far is symmetrical with respect to a horizontal plane passing centrally through the block 19. It will also be clear from the drawings 5 that the mechanism is mounted on the bottom wall 10 with one edge of the transformer core block 19 adjacent an edge of the said wall so as to afford a space at the other side thereof for the projection of the windings 20 and 21 laterally beyond the transformer core block 19.

Mounted on the bent-over portions 23 of brackets 22 are insulating elements indicated generally by the numeral 24. These elements are secured to the bent-over portions 23 by suitable bolts 15 and form both mounting and insulating means for the high tension ionizer. At the lateral edges of each of the insulating elements 24 are thin bosses or ribs 25 between which may be positioned a metallic plate 26 forming one electrode 20 of the ionizer. Centrally of each of the elements 24 is a higher upwardly extending boss 27 between which bosses a plate 28 of dielectric material, such as mica, may be placed in engagement with the upper surfaces of the bosses 25. 25 Resting on the plate 28 and separated thereby from the plate 28 is a wire mesh plate 29 having upturned edges as indicated at 30 for the purpose of preventing scratching of the mica plate 28, and for preventing accidental removal from 30 under the strip 31. From the drawings, it will be clear that longitudinal motion of the reticulated plate 29 will be limited by the angular portions of the strip 31 and, while it is not likely that any lateral motion might occur, this also 35 would be limited by the upturned side edges 30. The clamping strip 31 is secured to the upper surfaces of the bosses 27 and may be held in position by suitable bolts 32 passing downwardly through the bosses 27 and the main body of the 40 insulating elements 24 whereby to tie all the parts together.

Electrically and mechanically secured to the strip 31 as by means of one of the bolts 32 is a 45 conductor 33 coming from one side of the secondary winding 20. The other side of said secondary winding is soldered or otherwise connected to the plate 26 by a suitable conductor 34. A source of alternating current 35 has one side connected to 50 the primary winding 21 and the other side connected to the other end of such winding through a switch 36 which preferably embodies also a rheostat. Optionally a switch may be employed which connects to several spaced taps on the 55

winding 24 whereby to vary the voltage output of the transformer as desired.

While I have shown and described the present preferred embodiment of my invention, I wish it 5 understood that I am not limited to the details disclosed but only in accordance with the appended claims and the prior art.

Having thus described my invention, what I claim is:

10 1. In a device of the class described, in combination, an elongated transformer core carrying suitable transformer windings, spaced brackets mounted on said core and projecting beyond said windings, insulating plates carried by said brackets, a metallic plate electrode, a dielectric plate, and a reticulated electrode plate mounted on the upper surfaces of said insulating plates in the order named, means for connecting the terminals of one of said windings to said electrode plates and means for supplying current to the other of said windings, said insulating plates embodying spaced bosses between which said electrodes are positioned and a strip connected at its ends to said bosses and having a central depressed portion engaging said reticulated electrode plate.

2. In a device of the class described, in combination, an elongated transformer core carrying suitable transformer windings, spaced brackets mounted on said core and projecting beyond said windings, insulating plates carried by said brackets, a metallic plate electrode, a dielectric plate, and a reticulated electrode plate mounted on the upper surfaces of said insulating plates in the order named, means for connecting the terminals of one of said windings to said metallic plate electrodes and means for supplying current to the other of said windings, said insulating plates embodying spaced bosses between which 35 said plates are positioned and a metallic strip connected at its ends to said bosses and having a central depressed portion engaging said reticulated electrode plate, said strip being connected to one end of the secondary winding and forming the means of conducting current to said reticulated electrode plate.

3. In a device of the class described, in combination, a relatively flat transformer core carrying suitable primary and secondary windings, 40 two pairs of spaced brackets connected one pair to each face of said core and extending beyond

said windings, one pair of said brackets being connected to a supporting plate and the other pair thereof carrying an ionizing device, said brackets being U shaped and terminating at their ends in bent over portions all extending in the direction of the lateral projection of said windings beyond the transformer core, the projections of said ionizing device and of said transformer on said supporting plate being approximately co-extensive.

4. In a device of the class described, in combination, a generally flat transformer core carrying suitable primary and secondary windings thereon, spaced brackets carried by said core and extending substantially perpendicular to said core and beyond the said windings, spaced insulating means carried, one by each of said brackets having generally flat portions on their surfaces opposed to said core and each provided with a boss upstanding from such surface, an ionizer 20 assembly comprising flat electrodes separated by a flat sheet of dielectric mounted on said surfaces, a strip carried by said bosses and holding said electrodes and dielectric in assembled relation against said surface, means for connecting 25 said secondary winding to said electrodes and means for supplying alternating current to said primary winding, the outermost of said electrodes being a reticulated plate.

5. In a device of the class described, in combination, a generally flat transformer core carrying suitable primary and secondary windings thereon, spaced brackets carried by said core and extending substantially perpendicular to said core and beyond the said windings, spaced insulating means carried, one by each of said brackets having generally flat portions on their surfaces opposed to said core and each provided with a boss upstanding from such surface, an ionizer 30 assembly comprising flat electrodes separated by a flat sheet of dielectric mounted on said surfaces, a strip carried by said bosses and holding said electrodes and dielectric in assembled relation against said surface, means for connecting 35 said secondary winding to said electrodes and means for supplying alternating current to said primary winding, the outermost of said electrodes being a reticulated plate.

ARTHUR W. CONLEY. 50
